UNITED STATES PATENT OFFICE.

ELBRIDGE C. DOOLITTLE, OF PHILADELPHIA, PENNSYLVANIA, ASSIGNOR
OF ONE-HALF TO ALFRED R. JUSTICE, OF SAME PLACE.

BURNISHING-MACHINE.

SPECIFICATION forming part of Letters Patent No. 601,461, dated March 29, 1898.

Application filed June 18, 1897. Serial No. 641,299. (No model.)

To all whom it may concern:

Be it known that I, ELBRIDGE C. DOOLITTLE, a citizen of the United States, residing at the city and county of Philadelphia, State 5 of Pennsylvania, have invented certain new and useful Improvements in Burnishing-Machines, of which the following is a full, clear, and exact description, reference being had to the accompanying drawings, of which—

10 Figure 1, Sheet 1, is a plan view. Fig. 2 is a detail in elevation, broken away, showing the switch-block for raising the nut-piece carried by the moving table out of engagement with the threaded shaft. Fig. 3 is an elevation 15 of the said nut-piece removed. Fig. 4, Sheet 2, is a vertical section, as on line xx , Fig. 1. Fig. 5 is a front elevation. Fig. 6 is an elevation of a form of burnishing-tool such as shown in Figs. 4 and 5, but showing 20 the bloodstone tip thereof inclined to the shank of the tool. Fig. 7 is an elevation of a modified form of burnishing-tool and holder.

This invention relates to machines for burnishing plane surfaces of silverware or the 25 like—such as waiters, trays, &c.—and has for its object the production of a machine of the kind which shall be automatic in its operation of causing the burnishing-tool to regularly and gradually traverse the surface to 30 be operated upon.

A leading feature of the invention consists in the combination, with a suitable holder for the burnishing point or head, usually a bloodstone, of a sliding support or table for the 35 article to be burnished, means for reciprocating said point as it bears upon the surface of the article, and means for imparting to the said support—that is, in effect, to the article to be burnished—a gradual movement in a 40 direction at an angle to that of the reciprocatory movement of the burnishing-point.

Other features relate to certain details of construction and combinations of mechanism for the attainment of the object of the invention in the best and simplest manner, as hereinafter described and duly pointed out.

Referring to the accompanying drawings, forming a part of this specification, 1 is the frame that supports the mechanism of the 50 machine.

2, Figs. 1 and 4, is the main or driving

shaft, that is journaled in bearings of posts 1^a of the frame and is driven from a source of power.

3 is a second shaft, also journaled at each end in bearings of the frame and is adapted to be driven by a belt 4, Fig. 1, running over pulleys 5 and 6 on the ends of shafts 2 and 3, respectively. A part of the shaft 3 is screw-threaded, as shown. 55

7 is a horizontal table or support having legs 8, whose free ends rest upon guide-rails 9 of the frame in a manner to permit the said legs to slide longitudinally upon the rails. At the end of the table toward the threaded 65 part of shaft 3 is a forward extension 10, having a vertical slot 11 therein that is adapted to receive a bar 12, which I term the "nut-piece," whose lower end at 13 is semicircular and is screw-threaded to correspond with the 70 threads of the shaft 3, whereby when the nut-piece is in place within the slot its thread engages that of the shaft.

Adjacent to the outer end of the threaded part of shaft 3 is a clamp-yoke 14, that is secured to the guide-rails 9 by a set-screw 15. This yoke carries an incline 16, whose base is close to the shaft 3 and whose point is directed toward the nut-piece 12. 75

The article T to be burnished is placed upon 80 the table 7, to which it is suitably held—as, for instance, by means of clamp-yokes 17, whose end limbs engage the edge of the table and are held thereto by thumb-screws 18.

On the end of the main shaft 2 is a crank 85 19, to which is pivotally secured a jointed horizontal bar 20, that is adapted to slide in a guideway 21 of a post 22 of the frame. The rotation of the shaft imparts a horizontal reciprocating motion to the bar. I usually connect the said bar with the crank in such manner that the same may be adjusted so that the extent of the reciprocation of the bar may be readily increased or diminished. The particular means which I have devised for this 90 purpose is as follows: 23 is a lug through an aperture of which the crank passes, the lug having also a pin 24, upon which the bar 20 is pivoted. The lug is secured to the crank by a set-screw 25. Thus the former, and with 95 it the bar, may be shifted with relation to the crank. The free end of the bar carries the 100

holder 26 of the bloodstone 27 or other suitable burnishing-point. This holder is vertically adjustable, it being held between jaws 28 of the bar and clamped and released by a thumb-screw 29. In this way the bloodstone 5 may be adjusted to suit the elevation of the article to be burnished. As it is sometimes desirable to adjust the tool in the arc of a circle, I pivot jaws 28, or the part to which 10 the holder is secured, to the end of bar 20 and hold it at the desired elevation by means of a set-screw 30. It also is sometimes desirable to have the bloodstone bear yieldingly 15 upon the article, in which case I dispense with the set-screw 30 and employ a suitable spring to bear upon the pivoted part which carries the holder—as, for example, a flat spring 31, one end of which is secured to the bar and the other end bears upon the top of 20 the said pivoted part. By means of a screw 32 the tension or pressure of the spring may be regulated as desired. It is also sometimes desirable to change the bearing or working 25 point of the bloodstone, and to this end I secure the same to a piece 33, that is pivoted on a pin 34 to the holder 26, whereby the bloodstone may be moved laterally in the arc of a circle, as seen in Fig. 6.

Having now described the construction, I 30 shall proceed to describe the mode of operation of the mechanism.

The tray T or the like to be burnished is placed upon and clamped to table 7, the latter being then in such position that the line 35 of the bar 20 and of the bloodstone is near to the inner end of the tray that is toward the threaded part of the shaft 3, the stone resting upon the top of the tray at the edge of the part of the latter to be operated upon. 40 The main shaft is put in motion in the direction of the arrow in Figs. 1 and 4, and thus reciprocates bar 20 and at the same time, through the belt 4, drives the threaded shaft 3. The rotation of the latter by reason of the 45 nut-piece connecting the shaft and the table causes the latter to gradually advance at the same time that the bloodstone reciprocates across the surface of the tray. It will of course be understood that the pitch of the 50 screw-threads of said shaft and nut-piece and the relative speeds of rotation of said shaft and the driving-shaft are such that the movement of the table and tray shall not, so to say, be ahead of the traverse of the bloodstone, 55 and thus the entire surface of the tray will be burnished. As the machine continues thus in operation the nut-piece finally reaches the incline 16, and then riding upon it is thereby pushed upwardly and becomes disengaged from the screw-thread of shaft 3. The machine is now stopped. The tray is removed. The table is slid back to the original position ready to receive a second tray or the like, the nut-piece being also returned to 60 its original position in engagement with the threads of shaft 3.

It will be obvious that the extent of travel

of the table may be varied as desired by shifting the yoke 14 and consequently the incline. If the threads of the latter are square, 70 the nut-piece will usually remain in such engagement; but in order to insure against disengagement I prefer to use a suitable spring 35, whose free end bears against the top of the nut-piece. 75

In order to vary or adjust the speed of rotation of the shafts, I make use of nests of pulleys of different diameters thereon in the usual way, as shown.

I propose to sometimes use two bloodstones, 80 the one following the other in traversing the surface of the article being burnished. In such case I would employ the construction shown in Fig. 7—that is, I extend from each side of a vertical rod 26¹, that takes the place 85 of the holder 26, an arm 36 and connect to each arm a holder 37 for a bloodstone 38, and in order to cause the stones to bear evenly upon the surface to be burnished I would use flatsprings 39, (similar to the aforesaid spring 90 35,) whose free ends bear upon the tops of the holders, which latter are adapted to slide freely in slots in the said arms.

I do not limit myself to the particular construction or devices hereinbefore described, 95 as the same may be readily varied within certain limits by those skilled in the art to which the invention pertains without departing from the essential principle thereof.

Having thus described the construction and 100 *modus operandi* of my invention, I claim as new and desire to secure by Letters Patent—

1. In a burnishing-machine, the combination of the bar, the burnishing-tool carried thereby, the sliding table or support for supporting the article to be operated upon, the screw-threaded shaft disposed at an angle to said bar, a nut connected to said table and engaging said shaft, means for reciprocating said bar, and means for rotating said shaft, 105 whereby at the same time that the bar is caused to reciprocate with relation to said table, the latter is caused to advance with suitable relation to the movement of the bar, substantially as and for the purpose set forth. 115

2. In a burnishing-machine, the combination of the driving-shaft, the crank thereon, the sliding bar pivotally connected to the latter, means for securing a bloodstone or other suitable burnishing-tool, to the free end of said bar, the sliding table or support for holding the article to be operated upon, the threaded shaft driven from the said driving-shaft, and the nut connecting said shaft and table, all constructed and adapted to operate substantially as and for the purpose set forth. 120

3. The combination of the table, the rotatable screw-threaded shaft, the vertically-movable nut-piece, connecting the table and shaft, and the incline adapted to force the nut-piece out of engagement with the said shaft, substantially as and for the purpose specified. 130

4. The combination of the sliding table

mounted upon suitable guideways, the screw-threaded driven shaft, the nut-piece adapted to slide in a slot in said table, the incline adapted to engage said nut-piece and elevate the same out of engagement with said shaft, together with means for adjusting the incline with relation to the shaft and table, substantially as and for the purpose described.

In testimony whereof I have hereunto affixed my signature in the presence of two subscribing witnesses.

ELBRIDGE C. DOOLITTLE.
